SWIMMER'S BOAT

Filed July 5, 1945

UNITED STATES PATENT OFFICE

2,470,725

SWIMMER'S BOAT

Gustaf W. Rydner, Detroit, Mich.

Application July 5, 1945, Serial No. 603,389

5 Claims. (Cl. 9—18)

1

My invention relates to a new and useful improvement in a swimmer's boat adapted for use by a swimmer and so constructed and arranged that the swimmer may be free to carry on usual swimming activities and yet be enclosed in a device which will afford the swimmer safety.

It is an object of the present invention to provide a device of this class which will be simple in structure, economical of manufacture, durable, compact, light, and highly efficient in use.

Another object of the invention is the provision of a device of this class so arranged and constructed that it may be folded into compact form when not in use.

Another object of the invention is the provision of a device of this class having a supporting frame and carrying at opposite ends a buoyant body.

Another object of the invention is the provision in a device of this class of means for supporting a swimmer's body and allowing free use of his arms for operating a pair of oars which are mounted on the supporting frame.

Another object of the invention is the provision in a device of this class of a supporting frame provided with supporting bodies whereon the swimmer may rest when not swimming.

Another object of the invention is the provision in a device of this class of a frame so arranged and constructed that while the swimmer is in the normal position for swimming the frame will be in a position relative to the swimmer's arms so as to render assistance in supporting the body of the swimmer if necessary.

Another object of the invention is the provision in a device of this class of a pair of oars having swingably mounted paddles so arranged and constructed that when drawn in one direction through the water they will offer resistance and when drawn the opposite direction they will swing on their pivots to offer a minimum of resistance.

Another object of the invention is the provision in a device of this class so arranged and constructed as to embody a frame so that the center of gravity of a swimmer who is positioned within the frame will be below the frame proper while at the same time the side members will be passing under the arms of the swimmer in order to render support if necessary.

2

Other objects will appear hereinafter.

It is recognized that various modifications and changes may be made in the detail of structure illustrated and it is intended that such variations shall be embraced within the claims which form a part hereof.

Forming a part of this specification are drawings in which,

Fig. 1 is a top plan view of the invention,

10 Fig. 2 is a side elevational view of the invention,

Fig. 3 is an enlarged sectional view taken on line 3—3 of Fig. 1,

15 Fig. 4 is a sectional view taken on line 4—4 of Fig. 1,

Fig. 5 is an enlarged fragmentary elevational view taken on line 5—5 of Fig. 1,

Fig. 6 is an enlarged sectional view taken on line 6—6 of Fig. 5,

20 Fig. 7 is an enlarged sectional view taken on line 7—7 of Fig. 5,

Fig. 8 is a sectional view taken on line 8—8 of Fig. 1, slightly enlarged,

25 Fig. 9 is an enlarged sectional view taken on line 9—9 of Fig. 2,

Fig. 10 is a sectional view taken on line 10—10 of Fig. 8.

As shown in the drawings the invention comprises a supporting frame formed from a pair of sections. One of the sections embodies the oppositely disposed upper side rails 15 and 16 angularly turned at 17 and 18 to meet and preferably formed integral. A connecting bar 19 serves to connect similarly shaped and formed lower rails 20 and 21 to the upper rails. The inner end of the rails 16 and 21 and the inner ends of the rails 15 and 20 are connected to a plate 22 which is provided with a channel 23 and a tongue 24. The other section of the frame is similarly formed and comprises the oppositely disposed upper rails 25 and 26 angularly turned as in 27 and 28 to meet and preferably formed integral. Positioned beneath and in alignment with the rails 25 and 26 are the rails 32 and 30 with the angularly turned portions 31 and 33 which meet and are connected by the connecting bar 29 with the frame positioned above. The inner ends of the rails 25 and 32 connect to a plate 34 as do likewise the inner ends of the rails 30 and 26.

50 This plate 34 is pivotally connected by means

of the pin 35 to the member 22 and the plate 34 is provided with a head 36 which seats in the channel 23 and over which lies the tongue 24 thus hingedly connecting the two sections of the frame together. The tongue 24 is provided with a slot 37 registering with a passage 38 formed in the head 34. Positioned in the slot 37 and the passage 38 is a locking plate 39 which is held in position by a wire or other suitable cord 40 passed around the member 34 and through the plate 39. The cord 40 serves to retain the plate 39 in position and while this plate is in position swingable movement of the frame sections is of course prevented.

A cross bar 41 is provided on its opposite ends with the sleeves 42 which are slidably positioned on the rails 30 and 32. Projecting upwardly from the center of this cross bar 41 is the pin 43 on which is pivotally mounted the ends of the oars 44 and 45. On the outer end 46 of each of these oars is provided a pair of lugs 47 and 48 through which a rod 49 is passed to provide a pivotal mounting for the paddle forming sections 50 and 51 which may swing on the rod 49 but which are normally held in alignment with each other by means of the spring 52. Connecting the rails 25 and 26 together is a rod 54 in alignment with a rod 55 which serves to connect the rails 30 and 32 together. A cord 53 serves to connect the pin 43 to the rod 54 so that the cross bar 41 may slide on the rails 30 and 32 in one direction but not in the other.

Mounted on one end of the frame is buoyant member or tank 56 which is hollow and air-tight and held in position by the cord or wire 57. A similar tank 58 is mounted on the opposite ends of the frame and held in position by the cord or wire 59. The cord 57 and the cord 59 pass around the connecting posts 67, 68 and 69 which serve to connect the aligning portions of the upper frame with the lower frame.

A cross bar 60 serves to connect the rails 15 and 16 and together with the brackets or lugs 61 serves as a support for a pillow or a seat. The cross bar 62 may serve as a seat or a foot rest. When a person is reclining on the structure the head and shoulders may rest upon the pillow supported by the lugs or brackets 61 and the cross bar 60 and the person's feet would be supported by the cross bar 62.

Connected to and depending from the rails 15 and 16 are the supporting arms 63 and 64 which serve to support or carry the flexible belt or frame 65. It will be noted that this belt 65 is positioned below the lower rails of the frame.

In use a swimmer should thrust the body through the belt 65 and tighten it about his waist thus leaving his feet projected downwardly and being free to use his arms while at the same time he would also have the free use of his legs. In this manner a person could swim in water with security and safety. Because the attachment of the body to the frame is at a low position a tipping over of the frame is prevented. While in this position the swimmer could use the oars 44 and 45 to propel the supporting frame. As the oars move in one direction the paddle sections 50 and 51 would be in the relative position shown in Fig. 5 or Fig. 6. When the oars are moved in the backward direction the sections would swing toward each other or collapse so that a minimum resistance would be offered upon the return stroke of the oars. By adjusting the length of the cord 53 the location of the oars may be moved to various positions on the frame

to accommodate persons with different arm lengths. The person using the device could also, after the frame 65 has been buckled in closed position, rest upon the frame or supporting belt 65 with his body submerged to approximately the neck. Should the person desire he may lie prone on the supporting frame with his head and shoulders resting on the pillow or pad and his feet supported by the cross bar 62. The tanks at opposite ends project outwardly beyond the sides of the frame and thus serve to further resist any tilting movement of the frame. These tanks will provide the necessary buoyancy to the frame while at the same time they may be made sufficiently small so that the device will not be cumbered.

When desired the locking plate 39 may be removed and the frame may then be folded upon itself so that it may be packed away in a small space for transporting or carrying. It will be noted that when the swimmer is secured by the belt 65 he will always be in a position where if necessary he may grasp the oppositely disposed side rails.

Thus I have provided a simple and light and compact supporting frame whereby an inexperienced swimmer or even novice learning to swim may enter the water and have a feeling of safety and security thus adding to the confidence of the individual and rendering it possible for the individual to learn swimming quicker and easier.

What I claim as new is:

1. A device of the class described comprising a pair of frame sections hingedly connected together at their opposed ends, each of said sections comprising an upper frame and a lower frame positioned in alignment with each other and embodying spaced-apart rails; means for locking said sections against relative swingable movement; supporting arms on the upper rails of one of said sections and projecting below the lower rails of the corresponding section; and a supporting belt carried on the lower end of said supporting members for supporting a body at a point below the lowermost rails of said frame.

2. A device of the class described comprising a supporting frame embodying a pair of sections hingedly connected together at opposed ends, each of said sections comprising an upper frame and a lower frame embodying oppositely disposed side rails the upper frame and the lower frame being in alignment with each other; a buoyant member on the outer end of each of said sections and lying between the lower and upper frames of said section; and means on one of said sections for supporting a person's body.

3. A device of the class described comprising a supporting frame embodying a pair of hingedly mounted sections each of said sections embodying an upper frame and a lower frame comprising oppositely disposed side rails the side rails of the upper frame being in alignment with the side rails of the lower frame; means for locking said sections against relative swingable movement; a supporting bar mounted on the lower rails of one of said frames and slidably longitudinally thereof; means for preventing slidable movement of said supporting bar in one direction beyond a pre-determined distance; and propelling means pivotally mounted on said supporting bar and movable relatively thereto.

4. A device of the class described comprising a supporting frame embodying a pair of sections hingedly connected together at opposed ends, each of said sections embodying an upper

frame and a lower frame comprising oppositely disposed side rails the corresponding rails of the upper frame being in alignment with the corresponding rails of the lower frame; a buoyant member positioned between the upper and lower rails of each of said sections adjacent the outer end thereof; and a body supporting means on the upper rails of each of said sections for supporting the body of a person lying prone thereon.

5. A device of the class described comprising a frame embodying a pair of sections hingedly connected together at opposed ends each of said sections comprising an upper and lower frame embodying oppositely disposed side rails, the corresponding side rails of the upper frame being in alignment with the corresponding rails of the lower frame; supporting means connected to the upper rails of one of said sections and projecting downwardly therefrom below the lower rails of the same section; and a belt carried by the lower end of said body supporting means for

strapping about the body of a person using the same to support the body at a point below the lower rails of said section; and propelling means accessible to a person in said belt for propelling said frame through the water.
